(57) **CLAIM**

The ornamental design for a type font and electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a face view of a type font showing the claimed design;

FIG. 2 is a front view of an electronic device with graphical user interface showing the claimed design; and,

FIG. 3 is a front view of an alternate electronic device showing the graphical user interface of FIG. 2 applied thereto.

The broken lines in FIGS. 2 and 3 show an electronic device having a display screen, or an alternate electronic device having a display screen, and form no part of the claimed design.
